UNITED STATES PATENT OFFICE.

WILLIAM KELLY, OF DETROIT, MICHIGAN, ASSIGNOR TO MAXWELL MOTOR COMPANY,
INCORPORATED, OF DETROIT, MICHIGAN.

DESIGN FOR A MULTICYLINDER-ENGINE CASTING.

44,726.

Specification for Design.

Patented Oct. 14, 1913.

Application filed May 11, 1912. Serial No. 697,830. Term of patent 14 years.

To all whom it may concern:

Be it known that I, WILLIAM KELLY, a citizen of the United States, residing at Detroit, in the county of Wayne and State of Michigan, have invented a new, original, and ornamental Design for Multicylinder-Engine Castings, of which the following is a specification, reference being had to the accompanying drawing, forming part thereof.

The figure is a perspective of a multi-cylinder engine casting embodying my invention.

I claim,

The ornamental design for a multicylinder engine casting as shown.

WILLIAM KELLY.
